UNITED STATES PATENT OFFICE

THOMAS E. LANDVOIGT, OF WESTMONT, PENNSYLVANIA, ASSIGNOR TO NATIONAL RADIATOR CORPORATION, OF JOHNSTOWN, PENNSYLVANIA, A CORPORATION OF DELAWARE

RADIATOR

Application filed September 25, 1928. Serial No. 308,274.

My invention relates to radiators and particularly to panel radiators.

In heating rooms, particularly office rooms and residences, metallic radiators, constituted by a plurality of columns, are disposed about the walls of the room. Steam or hot water is circulated through the radiators and the surrounding atmosphere is heated in part by radiation and in part by convection currents passing upwardly between the columns of each radiator.

Where radiation is primarily relied upon to heat a large space, a material difference in temperature occurs between the atmosphere adjacent the radiator and the atmosphere at the extreme portions of the room. In order to obtain an average temperature throughout the room, it is necessary to maintain the radiator at a considerably higher temperature. This temperature is sufficiently high so that it is uncomfortable for a person to remain in close proximity to the radiator, with the result that the floor space adjacent the radiator is not available for other uses.

Such radiators have heretofore been made in standard shapes and sizes with little regard for harmonizing the appearance of the assembled radiator with that of other objects or furnishings in the room. Frequently, the spaces between the columns of the radiator serve as a dust collector. The dust is readily seen through the spaces between the columns and presents an untidy appearance. The spaces between the radiator columns present shadows which do not harmonize with the surrounding furniture or mural decorations.

Efforts have been made to cover radiators with shields of different types; such shields, however, require additional floor space and involve considerable additional expense. The surfaces of such shields must be perforated, or the shield must not completely fill an opening in order to provide for convection currents reaching the radiator.

I provide a radiator built up of radiator sections, each section comprising a plurality of columns in which the outer surfaces of the sections are provided with flanges, the

flanges of adjacent sections abutting each other to substantially close the spaces between the radiator sections. The space between the sections is turned into a stack. The configuration of the surfaces of the radiator sections is such as to obtain the maximum air velocity through the stack and at the same time expose a maximum metallic surface to the air. The area of the surface of each radiator section constituting an outer surface of the assembled radiator, is relatively small as compared with the surface enclosed within the stacks. Accordingly, the radiator depends upon the convectional movement of the columns of air through the stacks rather than upon radiation for heating the room. By providing a rapid circulation of the air in the room through the stacks of the radiator, it is possible to heat a room much more nearly uniformly than is possible where radiation is primarily relied upon.

The outer abutting surfaces of the radiator sections present a substantially uniform and continuous appearance to the outer surface of the assembled radiator. These surfaces may be decorated to harmonize with other objects in the room or with the walls of the room.

The accompanying drawings illustrate the present preferred embodiment of the invention, in which

Figure 1 is an end view of a radiator embodying my invention,

Figure 2 is a plan view thereof,

Figure 3 is a broken side elevational view of the radiator,

Figure 4 is a plan view of a radiator section,

Figure 5 is a sectional view thereof taken substantially along the section line V—V of Figure 1, and

Figure 6 is a view showing the application of an enclosing structure to the radiator.

Referring to the drawings, a radiator 2 is constituted by a plurality of sections 4 of similar shape. The sections 4 are provided with openings 5 through which clamping bolts 6 extend longitudinally of the

radiator, if push nipple pipe connections are used. Openings 7 are provided at the top and bottom of each section 4 for the reception of pipe connections 8, which may be either of the push nipple or screw nipple types.

In radiator sections heretofore used, the water columns have usually been of elliptical shape, presenting a narrow outer edge 10 with large open spaces between the columns both transversely and longitudinally of the radiator. I provide water columns 9 in each radiator section of a roughly rectangular shape whose outer surfaces terminate in 15 flanges 10 projecting the length of the maximum length of the radiator section and one-half the length of the intervening pipe connections 8.

Accordingly, when the radiator sections 20 4 are assembled and brought together, the edges of the flanges 10 engage each other and form substantially continuous outer surfaces for the radiator. The outer surface of each flange 10 is tapered slightly to provide draft for casting the radiator. However, the amount of the taper is not sufficient to detract from the paneled effect presented by the assembled radiator. The surface may be decorated if desired.

30 As the flanges 10 close the spaces between the radiator units, stacks 11 are formed within the assembled radiator. The edges of the radiator sections between the flanges 10 and the center of the radiator are provided with ribs 12 and 14. The ribs 14 are made shorter than the ribs 12 in order that the flow of air between the ends of ribs and the bulges of the radiator defining the openings 7 shall not be impaired. The ribs 10, 40 12 and 14 produce a scalloped effect when the radiator is looked at in plan. Accordingly, this construction also presents a large radiating surface to the air traversing the stacks formed between the radiator sections. 45 The cross-sectional area of each of the several stacks is designed to give a maximum velocity to the air traversing the radiator for better heating the room. A space 15 is provided between the water columns at 50 substantially the center of the radiator.

Referring to Figures 1 and 2, the radiator is suspended by supports 16 and 16a extending outwardly from a wall 17 or other support. The supports 16 extend through 55 openings 18 in certain of the flanges 10 and engage the hubs for the pipe connections. The ends of the supports 16 are provided with notches 19 for closing the bolts 6.

The supports 16a serve primarily to space 60 the radiator from the wall, or may be omitted, if desired. The position of the supports 16 on the wall 17 is determined in accordance with the air space desired below the bottom of the radiator. It is to be understood that the radiator may be sup-

ported by the customary legs, if desired, or by any other form of supporting device.

Referring to Figure 6, the radiator may be partially enclosed by a sheet metal housing or the like. Where the radiator is mounted in a recess in a wall, it often improves the appearance of the wall to place a closure over the spaces between the ends of the radiator and the wall, as well as at the top and bottom of the radiator. In 70 certain cases it is desirable to conceal the pipes connected to the ends of the radiator, in which case a closing device may be utilized. The surfaces of the closing device may be decorated or ornamented to harmonize with the appearance of the room or the panel effect on the radiator.

An example of such a closing device comprises a frame 20 having an opening 21 formed therein that fits over the outer face of the assembled radiator. The frame 20 conceals the pipes 22 connected to the radiator. The frame is solid at the ends of the radiator but is provided with openings 24 and 25 at the top and bottom of the radiator 80 respectively. The openings 24 and 25 are filled with grille work 26 for providing passageways for a current of air moving past the radiator. The material in the frame 20 is preferably metal, although other materials 90 may be used under conditions where there is no fire hazard or where the temperature at which they are maintained is not sufficiently high to cause deterioration thereof.

While I have shown and described the preferred embodiments of the invention, it is to be understood that it may be otherwise embodied within the scope of the appended claims.

I claim:

1. In a radiator, a plurality of matched sections joined together, the sections having oppositely directed vertical flanges thereon at the outer edges thereof which contact with the flanges of adjacent sections whereby the front and rear faces present a substantially continuous surface, said flanges terminating at the top and bottom of the sections whereby a plurality of open vertical flues are provided between the sections, and radiating fins on the sections of less width than the flanges projecting into the flues.

2. In a radiator, a plurality of matched sections joined together, the sections having oppositely directed vertical flanges thereon at the outer edges thereof which contact with the flanges of adjacent sections whereby the front and rear faces present a substantially continuous surface, said flanges terminating at the top and bottom of the sections whereby a plurality of open vertical flues are provided between the sections, radiating fins on the sections of less width than the flanges projecting into the flues,

said sections having central vertically elongated openings therethrough between the top and bottom thereof, some of the fins extending throughout the length of the column, and other of the fins at each side of the opening being of less height than the height of the openings.

In testimony whereof I have hereunto set my hand.

10   THOMAS E. LANDVOIGT.
